RECORDING AND PAPER FEED CONTROL
MECHANISM

Robert E. Boyden, San Gabriel, Bryan F. Kuhne, South Pasadena, and Wharton A. Parsons, La Canada, Calif., assignors to Clary Multiplier Corporation, San Gabriel, Calif., a corporation of California

Application September 10, 1951, Serial No. 245,794

4 Claims. (Cl. 235—60.25)

1

In instances where a considerable number of multiplication problems as well as additions and subtractions are performed, it is a usual practice to utilize key responsive, non-listing adding or calculating machines wherein the multiplicand factor of a multiplication problem, for example, is successively entered into the machine a number of times equal to the value of each multiplier digit, the product thus appearing on visible accumulator dials. Although such machines are satisfactory, the result must be transcribed onto paper by the operator for record purposes, resulting in a certain loss of time and possible chance of error.

In order to overcome this above-noted defect, conventional adding-listing machines are often used instead, the latter printing each factor as it is entered into the machine and also the totals or sub-totals. Although this is also satisfactory and often desirable when recording the factors of addition and subtraction problems, it causes considerable annoyance and waste of paper in recording multiplication and division problems in that the multiplicand factor, for example, is printed as an incident to each successive entry thereof in order to obtain the product.

Although non-print controls have been provided heretofore for selectively rendering the printing mechanism ineffective for certain operations, such controls must be manually reset during totaling in order to record the product of a multiplication operation or, if the controls are automatically retracted upon totaling, they must be again reset in order to continue further and successive multiplication operations.

It therefore becomes the principal object of the present invention to overcome the above noted defects of prior machines.

Another object is to control the printing mechanism of a listing machine of the above type in accordance with the type of operation of the machine.

Another object is to selectively control the printing mechanism of a listing machine to operate invariably or to operate in accordance with the type of operation performed by the machine.

Another object is to selectively set a listing machine of the above type to list all factors and totals or to list totals only.

A still further object is to automatically control the spacing or non-spacing of paper relative to the printing mechanism in accordance with the type of problem and the setting of printing mechanism controls.

The manner in which the above and other objects of the invention are accomplished will be

2

readily understood on reference to the following specification when read in conjunction with the accompanying drawings, wherein:

Fig. 1 is a plan view of a calculating machine embodying the present invention.

Fig. 2 is a longitudinal sectional elevation taken approximately on line 2—2 of Fig. 1 and illustrating the keyboard, rack, accumulator and printing mechanisms.

10 Fig. 3 is a sectional elevation illustrating the printer control knob and associated parts set in the "multiply" position and showing the parts prior to beginning of a machine cycle.

Fig. 4 is a sectional elevation of the total and sub-total bars and their connection to the printer control mechanism.

Fig. 5 is a sectional elevation of the non-add bar and its connection to the printer control mechanism.

20 Fig. 6 is a view similar to Fig. 5 but showing the non-add bar depressed and the printer control mechanisms set thereby.

Fig. 7 is a view similar to Fig. 3 but showing the printer control knob set to "add" position and 25 showing the machine at the printing phase of its cycle.

Fig. 8 is a view somewhat similar to Fig. 5 but showing the machine partially cycled and with the printer control mechanism set for printing under control of the total bar.

30 Fig. 9 is a sectional elevation illustrating certain parts of the printing mechanism in normal position as set by the control knob when moved to its "add" position shown in Fig. 7 and prior to the beginning of a machine cycle.

35 Fig. 10 is a view similar to Fig. 9 but illustrating the machine near the end of a cycle.

The particular embodiment of the invention disclosed herein is applied to the well-known and commercially available Clary adding machine of 40 which various operating instrumentalities are disclosed and claimed in the copending application of R. E. Boyden, S. N. 582,553, filed March 13, 1945 (since matured into Patent 2,583,810 issued on January 29, 1933) and in the patent to E. P. Drake, 45 2,472,696, issued June 7, 1949, wherein is disclosed and claimed the accumulator structure partially illustrated herein. Therefore, reference may be had to said application and patent for a disclosure of parts and details not specifically disclosed herein.

General arrangement

Referring to Fig. 1, the machine comprises in 55 general a computing section enclosed by a cover

11 provided with suitable openings 12, 13 and 14 for a roll of paper, a printing device and a platen operating knob 15, respectively. Another opening is provided in the cover 11 for a keyboard comprising amount keys 16 whereby amounts are set up to be entered into the machine. Additive entry of amounts set up on the keyboard may be effected by depression of either of two add bars 17.

10 Total bars 18 and a sub-total bar 19 are provided to total or sub-total amounts stored in the accumulator which is generally indicated at 26 (Fig. 2).

15 Depression of a repeat bar 20 will additively and repetitively enter any amount set up by the keys 16 into the accumulator without clearing the keyboard so long as the bar 20 is held depressed.

20 A non-add bar 21 is provided to permit printing of an amount set up by the keys 16 without entering the said amount into the accumulator. A subtract bar 22 is provided to subtract or divide amounts set in the keyboard from amounts registered in the accumulator.

25 Also extending through an opening in the cover 11 is a control knob 23 peculiar to the present invention whereby the printer is preconditioned to operate in different selected manners.

Drive and racks

30 The machine includes a main shaft 25 which is motor driven through a cyclic clutch (not shown) under control of the various depressible bars 17 to 22, inclusive. Depression of any such bar engages the clutch and starts a cycle of operation of the machine including one complete rotation of the shaft 25.

35 The shaft 25 will (through means not shown) effectively mesh the gears of the accumulator 26 with a series of differentially operable dual purpose racks 27, each having an upper and a lower set of rack teeth 28 and 29, respectively. The racks 27 are differentially advanced by drive means hereinafter described until arrested by depressed ones of the amount keys 16. The racks are also retracted by the same drive means and are guided for fore and aft movement by a movable rod 30 and a stationary rod 35 extending through slots 32 and 33, respectively, provided in the racks.

40 The rod 30 is driven laterally, i. e., fore and aft of the machine, by the drive shaft 25 (through means not shown) and is yieldably connected to each rack by pairs of opposed drive latches 34 and 35. Each latch is pivotally mounted on the rod 30 and is provided with a roller 36 normally seated in a lateral depression or notch 37 formed at the closed end of the slot 32 in the respective rack.

45 The rollers 36 are normally urged apart and held in driving engagement with the notches 37 by a spring 38 extending between the tails of the latches 34 and 35 until the respective rack is arrested by an associated depressed key 16 or a zero block 39 at which instant the rollers 36 ride out of the notches 37 and along the slot 32, thereby permitting the rod 30 to continue forward to carry along any other unrestricted rack.

50 The racks 27 are provided with a series of shoulders 42 spaced apart distances slightly greater than the spacing between the stems of the amount keys 16 whereby, when a rack is advanced until arrested by a depressed one of the associated amount keys, it will move a number of increments equal to the value of the depressed key.

55 Normally, when no key in an order is de-

pressed, its associated rack 27 will be blocked from advancement by the zero block 39 carried by a key controlled latch-bar 43. Said zero block is normally positioned directly in front of one of the shoulders 42. However, upon the depression of an associated key 16, the stem thereof will slide vertically along aligned slots in two spaced key plates 44 and 45 and a camming projection or lug (not shown) thereon will become effective to move the zero block out of cooperative engagement with the shoulder 42, permitting the rack to be advanced forward until arrested by the striking of the proper shoulder 42 against the depressed key stem.

Accumulator

60 As disclosed in the aforementioned Drake Patent 2,472,696, the accumulator includes ordinarily arranged gears 40 rotatably journaled upon a shaft 41 and positioned to mesh with either the upper set of rack teeth 28 or the lower set of rack teeth 29 on the respective racks, thereby to additively enter into or subtractively remove from the accumulator amounts set up on the keys 16.

65 The accumulator is normally held in a neutral position (as shown in Fig. 2) wherein the gears 40 thereof are located out of mesh with both sets of rack teeth 28 and 29 until moved into mesh by mechanism (not shown) under the control of the various depressible bars 17 to 22, inclusive.

70 Amounts set up on the keys 16 are "added" into the accumulator by the depression of the bar 17 whereupon the gears 40 are raised into mesh with the teeth 28 and then the racks 27 are moved forward (to the left in Fig. 2) until stopped by the stems of depressed keys 16. The gears 40 are then lowered into their neutral positions prior to the return of the racks 27, leaving the "added" amount in the accumulator.

75 Amounts are similarly "subtracted" from the accumulator by depression of the subtract bar 22 whereupon the gears 40 are lowered into mesh with the teeth 29 prior to the forward movement of the racks and are raised into their neutral positions prior to the return of the racks.

Printer

80 The upper edge of each rack 27 is formed with a set of rack teeth 46 arranged in mesh with a pinion 47 positioned to drive a respective one of an ordinarily arranged series of idler gears 48 independently journaled on a rod 48a. Pinions 49 are respectively entrained with other racks 27 and other idler gears 48.

85 The printer is provided with a series of printing dials 50 each having a series of type characters formed around the periphery thereof. Each dial 50 is loosely journaled on a stud 51 carried by a respective lever 52 loosely keyed on a printer control rock shaft 53. A spring 52a urges the lever 52 toward a paper supporting platen 146 but the lever is normally restrained from such movement by the rock shaft 53.

90 A pinion 54 fixed to each dial 50 is continuously entrained with a pinion 55 loosely journaled on a stud carried by the respective lever 52, the pinion 55 being aligned to mesh with a respective gear 48 thereby completing a train of gears connecting each rack with a respective dial whereby any movement of a rack 27 to digitize an associated accumulator gear 40 will correspondingly digitize its respective dial 50.

95 A full explanation of the printing mechanism and its movement during a machine cycle may be

had by reference to Patent No. 2,515,692, issued July 18, 1950, to R. E. Boyden et al., said disclosed mechanism including a rock shaft 302 similar to the rock shaft 53 illustrated in the present disclosure.

Printer control

Normally, the shaft 53 is rocked clockwise during the printing phase of a cycle to provide leeway for a spring-urged snap printing action of the levers 52 under the urge of their springs 52a.

Mechanism for blocking the normal action of the shaft 53 in the present invention includes a pin 56 (Figs. 3 and 7) fixed on an arm of a dust cover lever 57 loosely journaled on the shaft 53 and urged clockwise by a spring 58. Another arm of the lever 57 is provided with an arcuate slot 59 embracing a pin 60 carried on a leg of a printer dust cover 61 pivoted on a fixed pin 62.

A link 63 connects the lever 57 to a cam follower 64 journaled on a rod 65 fixed in the side frames (not shown) of the machine. The cam follower is provided at its other end with a roller 66 spring urged against a cam 67 keyed on the shaft 25.

A second cam 68, also keyed on the shaft 25, acts upon a roller 69 carried on a cam follower 70 journaled on the rod 65. An arm 71 is adjustably secured on the cam follower 70 by a screw and slot connection 72. A roller 73 positioned in the path of the arm 71 is carried on one arm of a three-armed lever 74 suitably fixed on one end of the shaft 53. The latter lever is urged clockwise by a spring 75 having one end attached thereto at 76. An arm of the lever 74 is provided with a cam like face 77 located directly below the pin 60.

When the machine is in its full cycle position illustrated in Fig. 3, the cam 68 is effective to hold the cam follower 70 in a clockwise rocked position and the latter, in turn, maintains the lever 74 and printer shaft 53 rocked counterclockwise against the action of spring 75 to mesh the pinions 55 with the idler gears 48. In machine operations wherein the printer control knob 23 has been set in its "add" position shown in Fig. 7, the cam 68 will, when the printing phase of the cycle is reached, allow the cam follower 70 and lever 74 to be rocked by spring 75 so as to rock the printer control shaft 53 and allow the printer levers 52 to be actuated by their individual springs 52a, causing a printing operation to occur.

The control knob 23 is integrally mounted on a control knob plate 80 pivotally supported on a frame pin 81. The knob is yieldably maintained in either its "add" position shown in Fig. 7 or its "multiply" position shown in Fig. 3 by a centralizer pawl 82. The latter is pivoted on a frame pin 83 and is urged counter-clockwise by a spring 82a to maintain a roller 78 thereon in engagement with either one of two detenting notches 79 formed on the control knob plate 80.

The plate 80 carries a pin 84 having a slot connection with one leg of a bail 85 pivoted on a frame supported rod 86. The other leg of the bail 85 is provided with a pin 87 adapted to thrust against a bail 88 also pivoted on the rod 86 and spring urged clockwise as will be described later.

The bail 88 has one leg adapted to be moved into blocking relationship with the pin 56, as shown in Fig. 3, to prevent clockwise rocking of the lever 57. Thus, when the control knob 23 is moved from its "add" to its "multiply" position,

it will rock the bail 85 clockwise causing pin 87 to recede from the bail 88 whereby the latter may move into blocking relation with the pin 56 as shown in Fig. 3. Assuming the bail to be so located, when the cam 68 reaches the position shown in Fig. 7 wherein the printing operation would normally take place, the lever 57, which is now blocked in a counter-clockwise rocked position, will, through pin 60, likewise retain the lever 74 and shaft 53 from rocking clockwise under the action of spring 75, thereby preventing actuation of the printing mechanism. This control of the printing operation, however, is superseded during totaling and non-add operations as will appear hereinafter.

The leg 88a (Figs. 5, 6, 8, 9 and 10) of the bail 88 has an arm 89 having a pin 90 fixed thereto and pivotally carrying one end of a link 91 pivotally connected by a pin 92 at the other end to a bell-crank 93 pivoted upon a frame pin 94. A spring 95 will, through the link 91, urge the bail 88 clockwise against the pin 87, thus causing the bail 88 to normally follow the setting of the bail 85.

However, the bell-crank 93 may be moved clockwise against the urging of the spring 95 by a pin 96 carried on a plural armed bell-crank 97 pivoted upon a frame pin 98. Another pin 99 carried by the bell-crank 97 is adapted to engage a platen advancing pawl 100 having one end pivoted at 101 (Figs. 5 and 8) to a cam follower 102 actuated by a cam 102a on the shaft 25. The pawl 100 is provided with a bent over hook 103 adapted to engage the teeth of a printing-platen ratchet wheel 104 integral with the platen 146. A spring 105 attached at one end to an arm of the bell-crank 97 and at the other end to a lug on the pawl 100 provides a clockwise urge to the crank 97 and a counter-clockwise urge to the pawl 100 whereby to normally maintain the pawl 100 against the pin 99. A frame pin 107 limits clockwise movement of the bell-crank 97.

The bell-crank 97 is settable from the position shown in Figs. 9 and 10 wherein it enables the pawl 100 to engage and drive the ratchet 104 a single tooth space to that shown in Fig. 8 wherein the bell-crank enables the pawl 100 to drive the ratchet 104 three tooth spaces. This setting of the bell-crank 97 is effected under control of the total and sub-total keys 18 and 19. Thus, the paper is advanced a greater distance as an incident to a totaling or sub-totaling operation. For this purpose, the bell-crank 97 has a pin 108 connecting with a slot in one leg of a bail 109 pivoted upon the rod 86 and having a pin 110 in the other leg adapted to be engaged by a hook 111 of a floating lever 112 hereinafter described.

In the conventional adding machine, a pawl 113 (Figs. 5, 6, 8, 9 and 10) pivoted at 114 to the bell-crank 102 normally engages and advances a ribbon feeding ratchet wheel 115 but is prevented from such engagement at certain times in accordance with the present invention as will be described presently. A spring 117 normally urges the pawl 113 into engagement with the wheel 115.

The ratchet wheel 115 is integral with a gear 200 which meshes with a second gear 201 integrally connected to a printing ribbon spool 202 on which is wound a printing ribbon 203. The latter is passed around ribbon guides 204, 205 and 206 to a point where it extends across the platen 146 directly behind the printing dial 50. A similar spool arrangement (not shown) is provided on the opposite side of the machine, on which is mounted the opposite end of the ribbon.

A pin 116 is mounted on the arm 89 of bail 88 and underlies the feed pawl 113. Thus, when the bail 88 is rocked clockwise, to effect blocking of the printer shaft 53, the pin 116 will raise the pawl 113, as illustrated in Fig. 5, out of engagement with the ratchet 115 to disable the ribbon feed.

The aforementioned pin 90 on the arm 89 of bail 88 also engages a slot 118 in one leg of a bail 119 pivoted upon a frame supported rod 120 and having another leg carrying a pin 121 adapted to be engaged by one end of a lever 122 (Figs. 5 and 6) pivoted on a frame pin 123. The pin 121 has no engagement with any other member. The lever 122 is engaged at its other end by a slot connection 124 with a pin 125 carried conventionally by a non-add bell-crank 126 whereby the non-add bar 21, when depressed, moves the crank 126 and lever 122, thereby through the pin 121, rocking the bail 119 clockwise. The latter, through the pin 90, rocks the bail 88 counter-clockwise against the action of spring 95 even though the control knob 23 may be set in its "multiply" position whereby to lower the pin 116 away from the pawl 113 so that the latter may effectively engage the ratchet 115. Obviously, the blocking leg of bail 88 is also moved out of engagement with the pin 56 of lever 57 so that the printer mechanism may function. Said counter-clockwise movement of the arm 89 also moves a pin 128 carried by the bail leg 88a away from the pawl 100 which is thus moved by the spring 105 into driving relation with the platen ratchet 104.

A similar restoration of the printing and ribbon feeding mechanisms is effected by depression of either the total bar 18 or the subtotal bar 19. The latter engage pins 129 carried by respective pivoted arms 18a and 19a which are spring urged upward in a manner not shown in order to normally hold the bars 18 and 19 in raised position. The pins 129 are connected to and support opposite ends of a link 130 having a pin 131 intermediate its ends and engaging a slot 132 in one end of a link 133. This link is pivoted on a pin 134 carried at the left end of the floating lever 112.

It is necessary during totaling and sub-totaling operations to return the accumulator to its zero position and the lever 112 is part of the conventional mechanism for rocking a zero stop shaft 135 carrying various zero stops into cooperative relation to the accumulator. For this purpose, the lever 112 is connected, through a pin and slot connection 137 to an arm 136 fastened to the shaft 135. The lever 112 is slidably fulcrumed over a frame pin 138 and, a shoulder 139 near its right hand end is raised, upon depression of either the total or sub-total bar, into the path of a pin 140 carried by a cam follower 141 pivoted on the rod 65. The latter cam follower also has a pin connection 142 with a hook 143 provided to raise or lower the accumulator in a manner not shown.

The follower 141 is rocked clockwise against the action of a spring 145 by a cam 144 keyed on the shaft 25, thereby causing the pin 140 to move the lever 112 to the left. During such movement, the hook 111 on the lever 112 engages the pin 110 to rock the bail 109 clockwise which, through the pins 108 and 98 on the crank 97, rocks the bell-crank 93 clockwise, the link 91 and the pin 99 thereby rocking the bail 88 counter-clockwise against the action of the spring 95 to the position seen in Fig. 7 wherein it is ineffective to block the printer from operation.

During a "total" operation, and after the bar 18 has been depressed, there is a point in the machine cycle where the roller on the cam follower 141 is urged by the spring 145 into the low part 5 of the cam 144 thereby retracting the hook 111 away from the pin 110. This is prior to the spacing of the paper by the platen 146 due to the impulse imparted by the pawl 100. Therefore, provision is made by means of a hook 147 (Figs. 4 and 10) for retaining the pin 110 in the position shown in Fig. 8. Otherwise, the combined action of the spring 95, the spring 105 and the pin 128 would be to push the pawl 100 into either the extreme position seen in Fig. 5 where it would be ineffective to actuate the platen or into the single space position seen in Figs. 9 and 10 depending, respectively, on whether the knob 23 was in its "multiply" position shown in Fig. 3 or in its "add" position shown in Fig. 7.

The hook 147 is pivoted upon the rod 65 and is urged downward toward the pin 110 by a spring 148 attached to a pin 149 embraced by a slot 150 in the body of the hook 147. The pin 149 is carried by a cam follower 151 pivoted upon the rod 65 and engaging a cam 152 keyed on the shaft 25.

Therefore, as the short cam 144 and its follower 141 allows the hook 111 to move away from the pin 110 the follower 151 will continue to ride 30 the high portion of the cam 152 causing the pin 149 to bear against the bottom of the slot 150 thereby maintaining the hook 147 in locking contact with the pin 110 until after the pawl 100 has rotated the platen 146.

Further description of the conventional function of the cams 144 and 152 and other associated parts is not deemed necessary for an understanding of the present invention, as reference may be had to the same in the aforesaid Boyden Patent 2,583,810.

Fig. 9 and Fig. 10 of the present drawings show the position of the parts in different cyclic positions when the knob 23 has been set to its "add" position shown in Fig. 7 wherein the parts are set for printing as an incident to each type of operation, i. e., add, subtract, non-add, totaling and sub-totaling.

Having thus described the invention, what we desire to secure by United States Letters Patent, is:

1. In a calculating machine, the combination of registering mechanism, paper feeding mechanism including a paper feeding element, printing mechanism for printing amounts on paper fed by said element, differential actuators for actuating said registering mechanism and for setting said printing mechanism, means for actuating said printing mechanism to print amounts set thereon, a ratchet operatively connected to said paper feeding element, a pawl for advancing said ratchet, means responsive to operation of said machine for operating said pawl through a uniform stroke, amount entry control means for causing said actuators to enter amounts into said registering mechanism, means responsive to said last-mentioned means for causing said pawl to engage said ratchet at a predetermined tooth position whereby to enable said pawl to advance said paper feeding element a predetermined amount, totaling control means for causing said actuators to take totals from said registering mechanism, means responsive to said last-mentioned means for causing said pawl to engage said ratchet at a different tooth position whereby to enable said pawl to advance said

paper feeding element a different amount, and printing control means selectively settable in one condition for rendering said actuating means invariably operable, said printing control means being settable in a second condition for rendering said printing mechanism actuating means operable during operation of said totalling control means and for rendering said printing mechanism actuating means inoperable during operation of said amount entry control means, said printing control means being effective when set in said second condition to prevent said pawl from engaging said ratchet during operation of said amount entry control means and to enable said pawl to engage said ratchet during operation of said totalling control means.

2. In a calculating machine, the combination of registering mechanism, paper feeding mechanism including a paper feeding element, a printing mechanism for printing amounts on paper fed by said element, differential actuators for actuating said registering mechanism and for setting said printing mechanism, means for actuating said printing mechanism to print amounts set thereon, a ratchet operatively connected to said paper feeding element, a pawl for advancing said ratchet, means responsive to operation of said machine for operating said pawl through a uniform stroke, amount entry control means for causing said actuators to enter amounts into said registering mechanism, means responsive to said amount entry control means for causing said pawl to engage said ratchet at a predetermined tooth position whereby to enable said pawl to advance said paper feeding element a predetermined amount, totalling control means, means responsive to said totalling control means for causing said actuators to take totals from said registering mechanism, means responsive to said totalling control means for causing said pawl to engage said ratchet at a different tooth position whereby to enable said pawl to advance said paper feeding element a different amount, disabling means for preventing operation of said printing mechanism actuating means and for preventing said pawl from engaging said ratchet, spring means for rendering said disabling means effective, printing control means selectively settable in one condition to render said disabling means ineffective, said printing control means being settable in a second condition enabling said spring means to render said disabling means effective, and means controlled by said totalling control means for invariably rendering said disabling means ineffective regardless of the setting of said printing control means.

3. In a calculating machine, the combination of a registering mechanism, paper feeding mechanism including a paper feeding element, a printing mechanism for printing amounts on paper fed by said element, differential actuators for actuating said registering mechanism and for setting said printing mechanism, yieldable means for actuating said printing mechanism to print amounts set thereon, a ratchet operatively connected to said paper feeding element, a pawl for advancing said ratchet, means responsive to operation of said machine for operating said pawl through a uniform stroke, amount entry control means for causing said actuators to enter amounts into said registering mechanism, means responsive to said last-mentioned means for causing said pawl to engage said ratchet at a pre-

determined tooth position whereby to enable said pawl to advance said paper feeding element a predetermined amount, totalling control means for causing said actuators to take totals from said registering mechanism, means responsive to said totalling control means for causing said pawl to engage said ratchet at a different tooth position whereby to enable said pawl to advance said paper feeding element a different amount, printing control means selectively settable in a first condition for blocking said actuating means from operation and for preventing said pawl from engaging said ratchet, said printing control means being settable in a second condition for unblocking said actuating means and for enabling said pawl to engage said ratchet, and means controlled by said totalling control means for invariably causing said printing control means to unblock said actuating means and to enable said pawl to engage said ratchet.

4. In a calculating machine, the combination of a registering mechanism, paper feeding mechanism including a paper feeding element, a printing mechanism for printing amounts on paper fed by said element, differential actuators for actuating said registering mechanism and for setting said printing mechanism, yieldable means for actuating said printing mechanism to print amounts set thereon, a ratchet operatively connected to said paper feeding element, a pawl for advancing said ratchet, means responsive to operation of said machine for operating said pawl through a uniform stroke, amount entry control means for causing said actuators to enter amounts into said registering mechanism, means responsive to said last-mentioned means for causing said pawl to engage said ratchet at a predetermined tooth position whereby to enable said pawl to advance said paper feeding element a predetermined amount, totalling control means for causing said actuators to take totals from said registering mechanism, means responsive to said totalling control means for causing said pawl to engage said ratchet at a different tooth position whereby to enable said pawl to advance said paper feeding element a different amount, printing control means including a manually settable member selectively settable in a first condition for blocking said actuating means from operation and for preventing said pawl from engaging said ratchet, said control means being settable in a second condition for unblocking said actuating means and for enabling said pawl to engage said ratchet, and means controlled by said totalling control means for setting said printing control means in said second condition, and a latch controlled by said totalling control means for latching said printing control means in said second condition.
